Primary Examiner — Mary Ann Calabrese*Assistant Examiner* — Jennifer L Rempfer(74) *Attorney, Agent, or Firm* — Mark M. Friedman(57) **CLAIM**

I hereby claim the ornamental design for the display screen with graphical user interface, as shown and described.

DESCRIPTION

The FIGURE is a front view of a display screen with graphical user interface presenting a television program banner. The dot-dot broken lines with the article show portions of the graphical user interface that form no part of the claimed design. The outer rectangle shown in long dash-dot broken line shows the display screen that forms no part of the claim.
